UNITED STATES PATENT OFFICE.

ACHILL BIPPART, OF NEWARK, NEW JERSEY.

CIGAR-CUTTER.

1,096,219.

Specification of Letters Patent.

Patented May 12, 1914.

Application filed April 7, 1913. Serial No. 759,298.

To all whom it may concern:

Be it known that I, ACHILL BIPPART, a citizen of the United States, residing at 788 South Tenth street, Newark, county of Essex, sex, and State of New Jersey, have invented 5 certain new and useful Improvements in Cigar-Cutters, fully described and represented in the following specification and the accompanying drawings, forming a part of 10 the same.

The object of the present invention is to furnish an improved construction for a cigar-cutter by which it is rendered very compact and of ornamental form, and made 15 of two plates pivoted one upon the other and the body-plate provided with a finger-hole through which the finger can be wholly inserted in holding and operating the cutter. The cutting-plate which is pivoted to the 20 body of the cutter is cut away upon one side to clear the finger when inserted in the finger-hole, and its end is formed as a finger-lever and extended beyond the edge of the body-plate, so as to be readily caught by 25 the finger-nail and thrown outward to insert the cigar-tip in the cutter.

The invention will be understood by reference to the annexed drawing, in which—

Figure 1 shows the rear side of the cutter 30 with the cutting-plate opened; Fig. 2 is an edge view of the cigar-cutter taken upon the right hand side of Fig. 1; Fig. 3 is a front view of the cigar-cutter; and Fig. 4 is a section on line 4—4 in Fig. 3 with the cutting- 35 plate closed, on double the scale of Fig. 3.

a designates the body of the cigar-cutter formed of a flat plate of oval shape with eyelet *b* at one end to serve as a hinged joint, and finger-hole *c* through the opposite end. 40 The cutting-hole *d* having beveled edges is formed in the plate next the eyelet *b*, and between such cutting-hole and the finger-hole a slot *e* is formed concentric with the eyelet *b*. The plate *f* is of semi-oval form like the 45 upper half of the body with a beveled cutting-notch *i* which coincides with one edge of the cutting-hole *b* when the cutting-plate is opened, as shown in Fig. 1, and a stop pin *j* is extended from the cutting-plate

50 near the lower edge of the notch *i* through the slot *e*, and has a head resting upon the opposite side of the body *a*, which holds the cutting-plate in close contact with the body *a* during the cutting operation, as the pin is 55 close to the notch. The inner side of the cutting-plate is cut away below the notch *i*,

to clear the finger-hole when the cutting-plate is fully closed, as shown in Fig. 3, to 60 cut the cigar-tip, the remaining portion of the cutting-plate lying at one side of the finger-hole when the plate is thus closed to form a finger-lever for opening the cutter; the extremity *g* of such lever being bent a little outside the edge of the body-plate *a* to be readily caught by the finger-nail for 65 opening the cutter. The cutting-plate thus conforms in its upper half to the oval shape of the body-plate *a*, while its lower half forms a finger-lever extending, when closed along one side of the finger-hole. A small 70 sloping projection *k* extends outward from the body near one end of the slot *e*, and a corresponding socket or recess *l* is formed in the adjacent face of the cutting-plate, which springs over the sloping projection when 75 the cutting-plate is closed, as in Fig. 3. This prevents the cutter from accidentally opening, whether carried as a charm or in the pocket. The oval form of the body *a* furnishes exactly the room required to locate 80 the cutting-hole and finger-hole in opposite ends of the body, with the curved slot between the same, which is longer than the width of the holes and thus requires the extra width at the middle of the body. 85

The connection of the two parts of the cutter by an eyelet furnishes a durable hinge, and at the same time an aperture through the hinge in which a ring or snap-hook can be engaged to suspend the cutter 90 as a charm, and the sloping projection and corresponding recess formed upon the opposite parts serves to hold the cutter closed when not in use.

It is common to form a cigar-cutter of two 95 parts sliding upon one another and their movement controlled by a pin in a slot, and I do not therefore claim such features broadly, but

What I claim and desire to secure by 100 Letters Patent is:

1. A cigar-cutter formed with an oblong body having hinge-pivot in one end and a finger-hole extended through the opposite end, a cutting-hole next the pivot and a 105 curved slot transverse to the body between the cutting-hole and the finger-hole, and a cutting-plate jointed to the hinge-pivot and having a notch to coöperate with the cutting-hole, and a stop-pin extended through 110 the slot, and a finger-lever extended from one edge of the cutting-plate, when closed,

along the side of the finger-hole, for opening the cutter when required.

2. A cigar-cutter formed with an oval body having eyelet in one end and finger-hole at the opposite end, a cutting-hole next to the eyelet and a curved slot transverse to the body between the cutting-hole and finger-hole, and a notched cutting-plate hinged upon the said eyelet and having semi-oval form with a finger-lever extended when closed by the side of the finger-hole and its end projected beyond the margin of the body

to be caught with the finger-nail, and a pin extended from the finger-plate through the slot with head upon the face of the body, 15 the whole arranged and operated substantially as herein set forth.

In testimony whereof I have hereunto set my hand in the presence of two subscribing witnesses.

ACHILL BIPPART.
